UNITED STATES PATENT OFFICE.

ALBERT TAPLIN, OF PROVIDENCE, RHODE ISLAND.

IMPROVEMENT IN LAMP-COLLARS.

Specification forming part of Letters Patent No. 41,795, dated March 1, 1864.

To all whom it may concern:

Be it known that I, ALBERT TAPLIN, of the city of Providence, in the county of Providence, in the State of Rhode Island, have invented an Improvement in Lamps; and I do hereby declare that the following is a full and correct description thereof, reference being had to the accompanying drawings, forming part of this specification, and to the letters of reference marked thereon, the same letters denoting like parts in all the figures.

Figure 1 is a view of the collar open. Fig. 2 is a view of the same closed. Fig. 3 is a view of the upper part of the collar. Fig. 4 is a top view of the lower part of the collar.

My improvement consists in making a collar in two parts, held together by a clasp on one side and a spring-catch on the other, to place between the common lamp-top and the burner that holds the wick, to afford easy access to the inside of the lamp for the purpose of filling it.

The collar is made of two parts, A B, which are shown in Figs. 3 and 4. These parts are punched out of sheet metal, and are pressed or swaged into the proper shape by means of dies. Fig. 4 shows the lower part of the collar B, and has a projection, C, left on one side to form a catch, and also a projection, a, on the opposite side to form the clasp-joint. This last projection is turned up, and has a narrow slot, x, cut in it to receive the part of the clasp on the upper part of the collar A. A portion of the metal is left at o to be slotted to receive the spring D. This part of the collar has a screw-thread cut on its lower end, s, to screw into the top of the lamp.

Fig. 3, which represents the top part, is made with a projection at c of the proper size to go into the slot x in the lower part, B. This forms the other part of the clasp, and is turned up so as to catch into the lower one. A

screw-thread is cut on the inside of the upper part, Fig. 3, of the collar at r to receive the screw on the lower end of the burner or wick-holder.

A spring, D, is fastened to the upper part, A, and slides through the slot o in the inside of the lower part. This spring is to hold the upper part of the collar up while open, and also to keep it from going too far back, the lower end of the spring being bent over to prevent it from coming entirely out of the slot.

The clasp-joint a c can be made at much less cost than the hinge-joint, as it requires less metal and labor in its construction.

The mode of operating it is simply as follows: The lower part of the collar B is screwed into the ordinary top of a lamp, and the burner or wick-holder is screwed into the upper part of the collar. When it becomes necessary to fill the lamp, the collar is opened by tipping back the burner in the direction of the clasp until the bent end of the spring D brings up against the side of the slot o, where the spring will hold it, so that it cannot be jarred or shaken down while the oil is being poured into the lamp. By bringing the burner back to place the collar is shut, and the catch l in front holds it firmly in that position.

Having thus described my improvement and the mode of operating it, what I claim as my invention, and desire to secure by Letters Patent, is this:

The combination of the upper and lower parts of the collar with the clasp-joint and spring D, when constructed and operating substantially as described, and for the purpose set forth.

ALBERT TAPLIN.
